TABULATING MACHINE

Robert E. Paris, New York, N. Y.

Application December 7, 1928, Serial No. 324,427

11 Claims. (Cl. 235—58)

This invention relates to improvements in tabulating machines and is shown as applied to a tabulating machine of the well-known Powers type such for instance as shown in U. S. Patent 1,236,481. The invention resides principally in mechanism to be inserted between the "pin-box" and "stop-basket" which takes the place of the usual "connection-box", and forms a flexible connection device between the pins and stops such connection device being manually settable to transpose data and to effect all that may now be accomplished by "Y-wires", "inverted Y-wires," "N-wire", etc., and to make it possible to set for different forms without removing the connecting mechanism commonly known in the art as the "connection-box" from the machine. This not only facilitates manipulation of the machine, but greatly cuts down the expense, for the present "connection-box" is so exacting as to manufacturing accuracy that each one is practically a hand-made job.

In order that such a mechanism could be constructed for the present Powers machine, it has been found necessary to create a novel preliminary representation device consisting of movable stop-lifters which are first set under control of the pins (themselves controllable by the punched record), to positions representing the data to be entered in the stops, and thereafter are all raised to enter the data on the stops. This device also permits an early ejection of the card or record from the machine and entry of another record, whereby speeding up the operation of the entire machine.

In constructing the flexible connection device, a sort of keyboard has been provided whereby electrical connections may be made so that data from one zone of the record or punched card may be entered at any desired place in the field of stops in the tabulator head. Thus data at the left-hand of the card may be printed by the right-hand unit of the tabulator or may be printed and added in a multiplicity of places in the adding head. This will be fully understood when the mechanism is understood in detail.

All of these objects are attained by mechanism shown in the accompanying drawings, in which:

Fig. 1 is a fragmentary, vertical front-to-rear section of a machine showing my invention and the correlated parts of a known tabulating mechanism.

Figs. 2, 3, and 4 are detail views of the elements of one of the preliminary representation devices.

Fig. 5 is a detail sectional view substantially

on line 5—5 of Fig. 1 and showing one of the bars carrying slides co-operative with the pins of the pin-box.

Fig. 6 is a horizontal sectional view of one of the controlling slides, taken substantially on line 6—6 of Fig. 1.

Fig. 7 is a front view of the control box.

Fig. 8 is a side view of the same.

Fig. 9 is an enlarged fragmentary horizontal section of the control box taken just inside the lower frame of the same.

Fig. 10 is a diagrammatic view showing characteristic wiring.

Like characters refer to like parts in all views.

Referring to the drawings in detail, and in particular to Fig. 1, the parts of well-known mechanism will first be described. The upper plate of a pin-box is indicated at 20, the pins being indicated at 21. In a well-known form of tabulator these pins operate wires of what is known as a "connection-box" to set stops. Such stops are shown at 22 as mounted in a "stop-basket" 23. These stops when raised are frictionally held raised until returned by means not here shown, but well known; and when raised, they control the excursions of actuating racks or segments and printing sectors. The cover for the tabulator head is shown at 24. Main frame members are indicated at 25 and 26.

A good sectional view of a Powers tabulator is given in Fig. 1 of the patent to Powers 1,236,481, in which the stop basket, connection-box and pin box and associated parts are shown.

Taking up next the new mechanism of the present invention, 27 and 28 represent front and rear cross bars upon which are removably mounted a series of rails 29, there being one rail 29 for each denominational row of pins 21 and located directly thereover. The rails may be suitably spaced by collars or washers and all rails are locked in place by a locking bar 30 extending across the rear ends of all of the rails. Each rail carries an adding slide 31 and a second slide 32 which are mounted for sliding movement longitudinally of their respective rails. The slides of each rail are constantly urged toward each other by a spring 33, but are normally held apart by universal cross bars 34 and 35.

The pins 21 are all grounded in any suitable manner, as for instance by grounding their guide plate 20. Each rail 29 is of inverted U-shaped cross-section and carries a contact plate 36, provided with a lead 38. The contact plates 36 are insulated from the rails 29 by insulating material indicated at 40. The slides 31 are constructed

from stampings, the lower edges of which are spaced apart at the bottom to carry pairs of contact strips 42. These strips are formed with springy fingers 43 pressing against plates 44 and the inner ends are bent sidewise so as to form a V-like throat as shown at 45. The strips 41 are separated from the slide members 31 by insulation strips 46. The leads 33 connect the several contact plates 43 with respective adding bars 30 which are mounted in a frame 47 secured to the front of the machine. The vertical strips or bars 30 are insulated from each other in any suitable manner and are formed with the front surfaces grooved longitudinally,—that is, the front surface is of V-shaped cross-section as clearly shown in Fig. 6.

Mounted in the frame 47 are bars 30 of insulating material upon which are mounted cross members or rails 38 one for each denominational row of stops 22, said rails 38 being preferably of rectangular cross-section, the bars 30 being of conducting material and each provided with a lead 31 which passes to one side of a respective electro-magnet 52, Figs. 1 and 9 and 10. The other side of the electro-magnet 52 is connected by a lead 53 to one side of a motor generator 54, the other side of which is connected by a lead 55 to the pin plate 20.

Mounted on each of the bars 30 is an adding slide 31. The slides 31 are preferably of insulating material and provided with finger-pieces 63 whereby they may be moved along their respective bars 30. Each slide 31 is provided with a V-shaped spring contactor 64 which is constantly in engagement with the respective bar 30 and the center portion of which may be moved into engagement with the grooved upper face of any one of the bars 46. It will thus be seen that by moving any slide 31 along its bar 30 any one of the adding plates 33 may be brought into circuit with the respective one of the electro-magnets 52. It will also be seen that by putting a plurality of slides 31 in contact with a single bar 46, a plurality of magnets 52 may be simultaneously actuated by action of a single slide 31. This is useful where data of a single card zone is to be entered on two or more accumulators of the tabulator head. There is one rail 29 for each row of pins 21, there being one row of pins 21 for each column 50 on the data or controlling card. There is one electro-magnet 52 for each row of stops 22, each row of stops 22 being associated with a respective accumulator wheel. Therefore, each bar 50 represents a respective one of the accumulator wheels and by properly adjusting the slides 31, any digit represented on the data card may be added to any accumulator wheel or plurality of such.

At the right and left hand sides and at the center of the frame 47 are grooved strips 66 which have no connections 38 and when the spring contacts 64 engage these bars no circuit can be closed for operating the respective electro-magnets.

The cross bars 34 and 35 extend through slots 68, Fig. 1 in the housing 69 of the rails 29 and are secured at their ends to respective links 70 and 71 at opposite sides of the housing. The links 70 are pivotally connected to the lower ends of rock arms 72 pivoted on a cross-shaft 73; and the links 71 are pivotally connected to the lower arms of rock levers 74 pivoted on a cross shaft 75. Links 76 and 77 connect one of the rock-arms 72 and one of the rock levers 74 with an eccentric strap 78 operable by an eccentric 79 mounted on a rotatable shaft 80 of the machine. While only one each

of members 71, 74, 72 and 73 is shown, in Fig. 1, it is to be understood that there is one of each at each end of the housing 69 so as to ensure parallel movements of the bars 34 and 35.

One rotation of shaft 80 corresponds with one cycle of the machine, and with the parts in the position shown in Fig. 1, it will be considered that a card has been fed to the pin box and that certain pins 21 have been raised to indicate the data punched in the card. The rotation of shaft 80 rotates eccentric 78 which causes arms 76 and levers 74 to draw bars 34 and 35 toward each other, and as bars 34 and 35 are moved, the slides 31 and 38 are moved by springs 44 to follow bars 34 and 35 until stopped by elements 44 shutting 16 against a raised pin. When the elements 44 contact a pin 21, a circuit is closed through that one of the electro-magnets with which the cooperative slide 31 is connected by one or more of the contactors 64. Of course, if no contactor 64 is positioned to be in circuit with the elements 44 of a slide 31, then no electro-magnet is operable thereby. However, when an electro-magnet is in circuit with such elements 44, and the circuit is closed by the elements striking a pin 21, that particular magnet is energized with results which will now be set forth.

Mounted on shaft 80 so as to be turned therewith is a cam 81, shown in Fig. 1. The cam 81 has a roller 82 riding on its periphery, such roller being mounted on the lower arm of a bell crank 83. The bell crank 83 is pinned on a cross-shaft 84 having a pair of substantially horizontal arms 85 extending under the stop basket 23, only one arm 85 being shown in Fig. 1.

Secured to the arms 85 is a cross-bar 86 so as to form a frame. Extending upwardly at each end of this frame is an ear 87, the ears 87 supporting between them a pivot rod 88, upon which are mounted the rear ends of rails 89, the connection being by slots in bars 89. There is one rail 89 for each row of stops 22 and arranged thereunder. The front ends of the rails 89 are mounted on a cross-rod 90 carried by ears secured to the frame member 25. Mounted on each rail 89 is a slide member 91 formed with a downwardly extending portion 92, and with a series of ten teeth 93. Each slide member 91 is also formed with four bent lips 94 by which it is retained on its bar or rail 89. For each slide 91 there is provided a stop actuator 95 which is formed with a spring ear 96, a bent over lip 97 and a stop-actuating finger 98. Each actuator 95 is slidably secured to its slide 91 by a screw 99 which passes through a slot 100 in its respective slide 91; and is held in any one of ten positions on the slide 91 by engagement of its lip 97 in any one of ten notches 101 formed in the upper edge of each slide 91. Springs 102 tend constantly to draw members 95 and 91 toward the right in Fig. 1, and to hold lips 97 in engagement with any desired notch 101, the fingers 98 extend laterally across members 95 so as to give wide upper or stop-operating faces. The slides 91 are normally held in left-most position by a universal bar 102 carried by links 103 secured to the upper arms of levers 74. The bar 102 may be supported and guided in a slot in a frame or other stationary member (not shown).

Each of the electro-magnets 52 is provided with an armature 104 to the free end of which is movably attached a stop-rod 105, the stop-rods of all of the magnets being guided at their upper ends in apertures in a stationary guide 75

plate 106. Each of the stop rods 105 is positioned under the slide 91 of the row of stops 22 with which the respective electro-magnet is associated.

5 When the machine starts to operate the rock levers 74 move the cross-bar 102 so as to permit the springs 1020 to draw the slides 91 along their respective rails 89. When the elements 44 of an operative slide 31 contact a raised pin 21, the 10 circuit is closed through the electro-magnet 52 with which it has been operatively connected and such magnet draws up its armature 104 thereby lifting its respective stop rod 105 until its upper end is in the path of one of the teeth 93 thereby 15 stopping further advance of that particular slide 91. Inasmuch as bar 102 controls the slides 91 to move in timed relation the slides 31, the stop rods 105 are raised so as to stop the bars 91 with the fingers 98 under the stops 22 corresponding 20 with the raised controlling pins 21. Thus if the 2 pin 21 is raised the corresponding or associated slide 91 will be stopped with its associated finger 98 under the 2 stop 22.

After the several fingers 98 have been positioned under the proper stops 22, cam 81 acts upon roller 82 to rock the bell crank 83 thereby raising rod 88 and with it all of the slides 91. These slides 91 in being raised bring the fingers 98 into contact with the lower ends of desired 25 stops 22, raising the latter so as to control the accumulators as is well understood in the art. In case no hole has been punched in a column of the card, the corresponding slide 91 will have moved its associated finger 98 beyond all stops 30 22 and no stop will be raised thereby.

45 A spring 107 holds arm 83 with roller 82 in contact with the periphery of cam 81. The ends of arms 85 are pivotally connected to a vertically reciprocating frame comprising side frames 108 and cross bars 109, the latter operating when the frame is lowered, to return the stops 22 to ineffective position. Since this frame moves up with arms 85, the cross-bars 108 are moved up ahead of the stops 22 and do not interfere with 50 the operation of the fingers 98.

Normally the lips 97 are located in the first notch 101 as shown in Fig. 1.

55 The remaining notches 101 are provided so that a number punched on the card may be arbitrarily changed when printed, as for instance when a hole in "9" position may indicate factory No. 3, so that it is desired to print "3", etc. This of course, would only be used in cases of split column work, where only a portion of a column of the record card was utilized for sensing a specific kind of data, such as factory numbers. While other uses might be found for this construction, such construction was developed with the split column feature in view.

60 The slides 31 are so positioned that when the elements 44 of a slide 31 reach the "9" pin 21, the corresponding finger 98 will be under "9" stop 22. This period of idle movement is provided because there are normally provided "11" 65 and "12" pins 21 which are ordinarily disregarded in straight tabulation. By arranging elements 81 and 101 the "11" and "12" pins may be utilized to effect desired code designations such as factory or warehouse numbers, etc. In 70 the Powers machine, as placed on the market, the "11" and "12" pins are used in conjunction with the alphabetic unit for controlling printing of letters, and in the numerical units additional signs or sign type may be placed on the numerical type sectors and controlled by such pins.

The adjustability of members 97 and 101 with relation to each other, therefore provides a means whereby such signs or alphabetic characters may be controlled in the printing head.

5 In the Powers tabulator as at present constructed Y-wires are used where it is desired to set up data from one zone of the card in the stops 22 of two units of the adding head. In the present instance the sliders 61 representing the desired denominations of the adding heads 10 are moved onto the bars 46 connected with the sensing members 36 of the desired card zone. For instance, if it were desired to enter data from the first column on the card, in the first row of stops of units one and two of the tabulator, then 15 the slides 61, numbered 1 and 11 in Fig. 7, would be moved onto the first bar 46 and if a "3" were punched in the first column of the card, the magnets 52 of the first and eleventh rows of stops 22 would be operated to hold the respective 20 fingers 98 under the "3" pins of these two rows.

When it is desired to transpose data, for instance from the first column of the card to the eleventh row of stops, the connection wire in the present Powers machine is bent so that the lower 25 end cooperates with a pin 21 of the first column and its upper end will operate a respective stop 22 of the eleventh row. With the present invention, it is only necessary to move the number eleven slide 61 into cooperative relation with the 30 first bar 46.

When it is desired to enter data from two columns of a card into a single row of stops 22, the present Powers construction, in commercial use, uses what are termed inverted Y-wires. In the present invention, this may be accomplished by moving the two slides 61 of the required one of the rails 50 into cooperative relation with the respective bars 46 corresponding to the columns of the card. When an electric impulse is then sent over either of these bars 46, it will operate the magnet 52 of the required common column. It must be born in mind that the use of inverted 45 Y-wires and of the present construction just mentioned, is limited to work where data will be punched in only one or the other of the columns of the card which are thus correlated to a single row of stops 22 of the adding unit.

50 These examples are illustrative of the work which may be performed by the described construction and are not intended to indicate the limits of the applicability of the device to various forms. It is however, suggestive to those skilled in the art of the necessary adjustments of slides 61 for any form desired.

55 It will now be seen that by properly adjusting the slides 61, data on a card may be added, or amounts may be added in a plurality of columns. Also the use of two sliders permits data from two columns of the cards to be entered in a single 60 column.

It will be seen also that the slides 61 and their members 95 form an intermediate representation device whereby the amounts may be retained and entered into the tabulator even after 65 the card has started to be ejected, thereby providing for rapid operation.

70 While I have described what I consider to be the most desirable embodiment of my invention, it is obvious that many changes could be made without departing from the spirit of my invention, and I, therefore, do not limit myself to the exact construction shown nor to anything less than the whole of my invention as hereinbefore described, and as hereinafter claimed.

2 claim:

- 5 1. The combination of a plurality of denominational series of card controlled elements; a plurality of movable members, one for each series of said elements, and controllable thereby; a denominational series of tabulator stops; and means including settable electric connections whereby any of said members may control selecting of said stops. 5
- 10 2. The combination of a denominational series of card-controlled elements, a member movable relatively to said elements and controllable thereby, a plurality of series of tabulator stops, and means including manually settable electric connections whereby said movable member may effect simultaneous control of selecting of stops of each of a plurality of said series of stops. 10
- 15 3. The combination with a plurality of rows of card-controlled elements and a plurality of rows of tabulator stops, of an electro-magnet operatively associated with one of said rows of stops, and means including settable electric connections for controlling said magnet from each of a plurality of said rows of elements. 15
- 20 4. The combination with a plurality of rows of card-controlled elements and a plurality of rows of tabulator stops, of a plurality of electro-magnets each operatively associated with a respective one of said rows of stops, and means including settable electric connections for controlling each of said magnets from each of a plurality of said rows of elements. 20
- 25 5. The combination of tabulator stops, preliminary representation devices for controlling selecting of said stops, electro-magnets for controlling said devices, card-controlled elements, and means controllable by said elements for controlling said electro-magnets and including mechanism settable for shifting the control of 30 said elements with relation to said electro-magnets. 30
- 35 6. The combination of tabulator stops, an electro-magnet for controlling selecting of said stops, a member in circuit with each of said magnets, a card-controlled element, a member in circuit with said card-controlled element, and settable means mounted on one of said members and operable for connecting said members. 45
- 40 7. The combination of tabulator stops, electro-magnets for controlling selecting of said stops, a series of members each in circuit with a respective one of said magnets, a plurality of card- 40
- 45 controlled elements, a series of members each in circuit with a respective one of said elements, and settable means mounted on the members of one of said series and operable to connect any member of one series to any member of the other series. 5
- 50 8. The combination of a denominational series of tabulator stops, a preliminary representation device operable to control any one of said stops, a card controlled element for setting said device in accordance with a perforation in a card, and means including manually settable members operable for setting said device so that said element may control said device to effect control of any desired one of a plurality of said stops from a single perforation position of a record card. 5
- 55 9. In combination a plurality of card sensing elements of respective denominational orders, a plurality of tabulator controlling elements of respective denominational orders, a plurality of slideable manipulative elements, and means including two groups of conductors arranged angularly with relation to each other and associated with said slideable manipulative elements to render any one of the first said elements capable of controlling any one of the second said elements. 20
- 60 10. In combination a plurality of card sensing elements of respective denominational orders, a plurality of tabulator controlling elements of respective denominational orders, a plurality of slideable manipulative elements, and means including two groups of conductors arranged angularly with relation to each other and associated with said slideable manipulative elements to render any one of the first said elements capable of controlling a plurality of the second said elements according to the setting of the manipulative elements. 35
- 65 11. In combination a plurality of card sensing elements of respective denominational orders, a plurality of tabulator controlling elements of respective denominational orders, a plurality of slideable manipulative elements, and means including two groups of conductors arranged angularly with relation to each other and associated with said slideable manipulative elements to render a plurality of the first said elements capable of controlling any one of the second said elements. 45
- 70 ROBERT E. PARIS. 50
